WEFT STOP MOTION FOR NARROW
WARE LOOMSAllan S. Hutchins, Oakham, Mass., assignor to
Crompton & Knowles Loom Works, Worcester,
Mass., a corporation of Massachusetts

Application February 2, 1949, Serial No. 74,069

12 Claims. (Cl. 139—371)

1

This invention relates to improvements in weft stop motions for narrow ware looms and it is the general object of the invention to provide such a motion which will be effective to stop the loom either upon weft breakage or weft slackness preceding substantial depletion of weft.

Narrow ware looms ordinarily operate with a large number of relatively small shuttles which are reciprocated on the lay by rack and pinion mechanism. The lay has a series of spaced shuttle blocks between which the warp sheds are located. The weft of each shuttle is usually wound on a small spool or quill which is rotatably mounted on the shuttle, and in the course of loom operation the thread from a quill may become either broken or sufficiently depleted to require replenishment. Narrow ware looms are ordinarily not equipped with any form of weft stop motion and considerable attention on the part of the weaver is required to watch the weft and stop the loom before any of the shuttles become depleted.

It is an important object of the present invention to provide a weft stop motion including a weighted arm or the like normally sustained by the weft but moving by gravity to an indicating or stopping position when the weft either breaks or becomes unduly slack. The weighted arm or detecting member when in stopping position is moved by the shuttle to close an electric switch, preferably located on the lay, thereby initiating loom stoppage.

The shuttle blocks of narrow ware lays are generally arranged in such manner that each block receives first one shuttle and then another shuttle. It is a further object of the invention to provide a weft stopping means so located with respect to a shuttle block as to be effective to stop the loom if breakage occurs in either of the two shuttles which may be received by the shuttle block.

Narrow ware shuttles ordinarily have spring tension means including eyes through which the weft is threaded when passing from the quill to the delivery eye on the bow of the shuttle. These tensions are ordinarily extended to produce the proper degree of tautness of the thread and the latter is therefore able to support the aforesaid weighted detector arm. Heretofore it has been customary to wind the entire length of weft on the quills in one direction so that as the weft unwinds it is kept taut by the tension means throughout the whole time that the shuttle is weaving.

It is another object of the present invention to

2

provide the quill with weft part of which has a reverse wind so that when this part of the weft is reached during the depletion of weft on the quill the thread will suddenly become slack although not broken and due to this slackness the weighted detector will be free to fall and effect loom stoppage. It is not necessary that all of the quills have this reverse wind, since the rate of consumption of the weft is likely to be the same for all shuttles, and it will suffice if only one quill has the reverse wind.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a front elevation of part of the lay of 20 the narrow ware loom having the invention applied thereto,

Fig. 2 is an enlarged plan view of one of the shuttles and its shuttle block looking in the direction of arrow 2, Fig. 1, and showing the detector arm in normal or raised position,

Fig. 3 is a vertical section on line 3—3, Fig. 2,

Fig. 4 is a view similar to a part of Fig. 2 but showing the detector arm in stopping position,

Fig. 5 is a diagrammatic view of a stopping 30 electric circuit which can be used with the invention,

Figs. 6 and 7 are diagrammatic views showing the reverse wind on the quill,

Fig. 8 is a perspective view of the weighted detector members which when in fallen position effects loom stoppage, and

Fig. 9 is a diagrammatic view taken in a direction across the quill showing the detector member and related parts.

Referring particularly to Fig. 1, the loom lay 40 L has a beam 10 in which a rack 11 is mounted for horizontal reciprocation by any of the well-known narrow ware shuttle motions not illustrated herein. This rack meshes with a series of pinions which in turn mesh with the shuttles. As shown in Fig. 1 four spaced shuttle blocks 12, 13, 14 and 15 are mounted on the lay and each shuttle block has rotatable therein one of the sheaves 16 meshing with the rack 11. Each block has shuttle guiding slots or grooves 17 and 18 and the blocks are so arranged that the curved slot 17 of one block will be concentric with the curved slot 18 of an adjacent block. The shuttles have the usual racks not shown on their under sides to mesh with the sheaves so that as the rack 11 is

reciprocated the shuttles move from one block to another across warp spaces 19 in which are located beat-up reeds 20. In Fig. 1 shuttles S1, S2, S3 and S4 are shown in the blocks 12 to 15, respectively, in readiness for movement to the left.

It will be apparent from Fig. 1 that during the running of the loom each block supports two shuttles alternately. Thus, block 14 is shown in Fig. 1 as supporting shuttle S3 for one beat-up of the lay, but on the next pick shuttle S3 will have moved to block 15 and shuttle S2 will have moved from block 13 to block 14. Block 14 therefore supports the shuttles S2 and S3, first one and then the other, during successive beat-up motions of the lay, and this is true of all except the end shuttle blocks.

Each shuttle as shown more particularly in Fig. 2 has a quill compartment 25 across which extends a pin 26 on which is rotatably mounted a quill or spool 27. The weft W is wound on the quill and a tension pad 28 is pressed against the back of the weft on the quill to resist rotation of the quill on the rod 26 and help tension the weft. The shuttle has movable tension eyes 30, 31 and 32 and a weft delivery eye 33. The weft extends from the top of the quill to and through the tension eyes 30, 31 and 32 in the order named and then out the delivery eye 33. It is not thought necessary to show the pull back springs associated with the eyes 30-32, since they are well understood, and it is thought sufficient to state that during loom operation these eyes will be extended as shown in Fig. 2 and keep the weft taut.

The matter thus far described is of common construction in narrow-ware looms and of itself forms no part of the present invention.

In carrying the invention into effect means are provided by which the loom can be stopped if the weft W either breaks or becomes slack to a degree which cannot be compensated for by retraction of the tension-eyes 30-32. This stopping means is preferably applied to each of the shuttles, but certain features of my invention do not require that each shuttle be thus equipped. Such shuttles as are equipped with the stop motion will be made as shown for instance in Figs. 2-4.

A stationary rod 35 is fixed into the shuttle and extends across the quill space 25. A light-weight detector member or wire 36 of the shape shown in Fig. 8 has eyes 37 and 38 in the ends thereof encircling the stationary rod 35. Stops 39 and 40 are located near the ends of rod 35 and may be formed as small pieces of wire having spaced coils 41 secured to the rod and joined by a stop link. Link 42 at the right, see Fig. 4, is below detector 36, while link 43 at the left is above it, and these links limit angular motion of the detector relatively to the shuttle. Each eye 37 and 38 is located between its corresponding coils 41 and endwise motion of detector member 36 on rod 35 is thus limited.

Secured to the lay beam is an electric switch 45 having an upright arm 46 extending from a switch box 47 held in fixed position on the lay. Arm 46 is normally in a back or non-stopping position, or toward the quill 27, thus enabling switch 45 to be normally open. If desired a resilient holding or detent wire 50 may be secured to the box 47, as at 51, and extends rearwardly and has an inclined end or finger 52 normally forward of arm 46.

Under normal conditions the weft will pass under the forward part 55 of the detector mem-

ber 36 in front of rod 35. So long as the weft is taut, as indicated in Fig. 2, it holds the detector 36 in raised non-stopping position with the weft engaging detector part 55 above the switch arm 46 and the switch therefore remains in its open position.

When the weft breaks, as indicated in Fig. 4, the detector wire 36 by its weight falls to a position under the rod 35 against stop link 42, and as the shuttle moves one or the other of two bent or cam sections 56 on detector 36 will pass behind and engage the upright arm 46 and move it forwardly to stopping position, thereby closing switch 45. The stop or limiting link 43, by its engagement with detector 36 near its eye 37, prevents the detector 36 from moving rearwardly beyond its normal or operating position when engaging the upright arm 46. As the switch arm 46 moves forwardly the detent 50 snaps behind it and holds it in its forward or closed position.

When switch 45 is closed the electric circuit shown in Fig. 5 is closed, this circuit including secondary 58 of a transformer T, the switch 45, wire 59, a solenoid 60, a stationary contact 61, plate 62 on a shipper lever 63 and wire 64 to the ground. Since the other side of the secondary 58 is also grounded this circuit will be energized, whereupon the solenoid lifts a link 65 into the path of a regularly oscillating lever 66, whereupon the latter moves the link to the right as viewed in Fig. 5 and rocks the shipper lever 63 to the right to effect loom stoppage and at the same time break contact between plate 62 and contact 61. For details of the stopping mechanism reference may be had to prior Patent No. 1,873,465.

The detent 50 serves the purpose of holding switch 45 closed after arm 46 has been moved forwardly by the detector wire 36, but this detent will not be necessary in all uses of the invention, since the circuit shown in Fig. 5 can be made sufficiently sensitive to actuate the solenoid 60 upon a brief closure of switch 45 such as might occur during the short time that a shuttle is relatively stationary in one of the shuttle boxes. Before restarting the loom the weaver will release arm 46 from the detent.

One feature of the invention is set forth in Fig. 1, where it will be seen that a stopping switch is provided for every other shuttle box. The switch thus far described and indicated at 45, is associated with shuttle block 14, but there will be another similar switch 70 in front of shuttle block 12, and similarly there may be a switch for every second shuttle block. From an inspection of Fig. 1 it will be apparent that on one beat of the loom switch 45 can be closed by the detector wire of shuttle S3, whereas on the next beat of the loom shuttle S2 will be on block 14 and its detector will also be able to close switch 45 if its weft is broken or slackened. The switch 45 is centrally located with respect to block 14 along the length of the lay, and this relationship is true of the other switch, and the shuttles, being similar and their guide slots 17 and 18 being alike for each block, each shuttle when moving to a shuttle block associated with a switch box will be able to effect loom stoppage if its detector 36 is in down position.

Another feature of the invention relates to stopping by effecting a slackness of the thread when a predetermined condition of weft depletion has been reached. Figs. 6 and 7 show diagrammatically the way in which the weft is

wound on the quill when this feature of the invention is used. The barrel 71 of the quill has a few residual wraps 72 of weft wound thereon. These wraps need not be many in number but will represent a sufficient length of thread to prevent complete exhaustion of the quill before the loom can be stopped by the stopping mechanisms. This inner body of weft is wound on the barrel in a right hand direction, starting at a point 73, see Fig. 6, and coiling around the barrel 71 for several turns in a clockwise direction. The weft is then reversed as at 74 and wrapped around the barrel in the opposite or counter-clockwise direction for several turns to produce a second body or layer 75 of weft which ends at a point 76. From the latter point the weft is again wound in a clockwise direction until the quill is full of weft to provide an outer layer 71.

The quill thus formed will have a small inner winding of weft of one hand and a much larger outer winding of the same hand, and there will be an intermediate winding of the reverse hand. If the reverse winding is made long enough it may be possible to dispense with the inner layer 72.

When a full quill wound as indicated in Fig. 6 is moved back and forth through the warp shed it will turn in a clockwise direction as viewed in Fig. 6 and the tension eyes 30-32 will keep the thread sufficiently taut to hold the detector 36 in the elevated position shown diagrammatically in Fig. 6. As weaving continues and the outer layer 71 of regular wound weft is used up the reverse winding is reached, whereupon conditions become as indicated in Fig. 7 and the yarn forming the reverse winds will loosen and produce more slackness than the tension eyes 30-32 can take up. The detector wire 35 will thereupon drop to its stopping or indicating position shown in full lines in Fig. 7. Loom stoppage will then result as already described, but the weft of the quill will be intact so that no mispick will occur in the cloth. If desired, the winding arrangement shown in Figs 6 and 7 can be used for all the shuttles, but this will not be necessary if all the quills have at least as much weft as is represented by layers 71 and 75 at the start of weaving. In that event a single quill will suffice and when its reverse winding is reached there will still be enough weft on the other quills to last until the loom is stopped. The weaver can then renew the weft in all the shuttles.

From the foregoing it will be seen that the invention sets forth a simple form of weft stop motion employing electric switch on the lay normally open but closed to energize a stopping circuit when a detector wire or member 36 falls to indicating position, due either to weft breakage or slackness, and is moved by the shuttle to close the switch. The resilient wire detent 50 can if desired be used to hold the upright arm 46 in closed position, and will of course be released by the weaver before weaving is resumed after loom stoppage. Also, the detector switch is located centrally of every second shuttle block in such position that it can cooperate with either of two shuttles which are alternately supported by the block. Furthermore, the reverse wind of the quill automatically produces an excess slackness of weft when a predetermined degree of weft consumption is reached, thereupon permitting the detector wire 36 to fall to stopping position even though the thread remains intact. Only one quill with a reverse wind is needed, provided all of the other quills have a

sufficient length of weft. The shuttle blocks have been shown with curved guide slots but the invention is not limited to such slots. When they are used centrifugal force aids gravity to move the detector 36 to stopping position.

Having thus described the invention it will be seen that changes and modifications of the foregoing specific disclosure may be made without departing from the spirit and scope of the invention.

What is claimed as new is:

1. In a weft detecting system for a narrow ware loom having a lay provided with shuttle blocks, a normally open electric switch on the lay in front of one of said blocks, a shuttle moving to said one block from another block during loom operation, a detector on the shuttle normally held in non-stopping position away from the switch by the weft in the shuttle when the weft is taut but moving to stopping position when the weft breaks or is unduly slack, the detector when in stopping position and due to motion of the shuttle from said other block to said one block effecting closure of said switch, and means effecting loom stopping incident to closure of said switch.
2. In a weft detecting system for a narrow ware loom having a lay provided with shuttle blocks, a normally open electric switch on the lay in front of one of said blocks, a shuttle moving to said one block from another block during loom operation, a detector on the shuttle normally held in non-stopping position away from the switch against the action of gravity by the weft when the latter is taut but moving by gravity to stopping position when the weft breaks or is unduly slack, the detector when in stopping position and moved by the shuttle from said other block to said one block effecting closure of said switch, and means effecting loom stopping incident to closure of said switch.
3. In a weft detecting system for a narrow ware loom having a lay and shuttle blocks spaced therealong, a shuttle moving in the general direction of the length of the lay from one of said shuttle blocks to another of said shuttle blocks, a weft detector in the shuttle normally in non-stopping position when the weft of the shuttle is taut but moving to stopping position when the weft is broken or unduly slack, a normally open electric switch on the lay closed by the detector when the latter is in stopping position and is moved by the shuttle lengthwise of the lay to engage the switch, and means to stop the loom incident to closure of said switch.
4. In an electric weft detecting system for a narrow ware loom having a lay provided with a shuttle moving in the direction of the length of the lay, a normally open electric switch on the lay, a weft detector in the shuttle normally held in non-stopping position when the weft of the shuttle is taut but moving to stopping position when the weft is broken or slack, said detector when in stopping position and due to movement of the shuttle along the length of the lay effecting closure of said switch, and means stopping the loom incident to closure of said switch.
5. In an electric weft detecting system for a narrow ware loom having a lay provided with a shuttle moving in a curved path, a normally open electric switch on the lay on the convex side of said path, a weft detector in the shuttle normally held in non-stopping position when the weft is taut and aided to move to stopping position by centrifugal force as the shuttle moves along said

path when the weft is broken or slack, said detector when in stopping position and due to movement of the shuttle along said path effecting closure of said switch, and means stopping the loom incident to closure of said switch.

6. In a weft detecting system for a narrow ware loom having a lay provided with three shuttle blocks arranged therealong, a pair of shuttles moving along the lay, one of said shuttles being supported by the intermediate block on one beat-up of the lay and the other shuttle being supported by said intermediate block on the next beat-up of the lay, a weft detector in each shuttle, each detector being held in non-stopping position when the weft of the corresponding shuttle is taut but failing to a stopping position when the weft therefor is broken or slack, a normally open electric switch on the lay in front of said intermediate shuttle block, either detector when in stopping position being effective to close said switch due to motion of the corresponding shuttle to said intermediate block, and means effective to stop the loom incident to closure of said switch by either detector.

7. In a weft detecting system for a narrow ware loom having a lay provided with a central shuttle block and a shuttle block on either side thereof, a pair of shuttles moving along the lay one of which is supported on said central block on one beat-up of the lay and the other of which is supported on said central block on the next beat-up of the lay, a normally opening electric switch on the lay adjacent to said central shuttle block, a weft detector in each shuttle, each detector being held in non-indicating position when the weft of its shuttle is taut but moving to stopping position when the weft of its shuttle is broken, either shuttle when moving toward said central shuttle block effecting closure of said switch, provided the detector corresponding thereto is in stopping position, and means stopping the loom incident to a closure of said switch.

8. In a weft detecting system for a narrow ware loom having two shuttles which alternately move along the lay toward a shuttle block on the lay, a normally open switch on the lay in front of said shuttle block, a weft detector in each shuttle moving from the normal position thereof to the stopping position thereof when the weft of the corresponding shuttle breaks, either detector when in stopping position and moved by the associated shuttle toward said shuttle block being effective to close the switch, and stopping the loom incident to closure of said switch.

9. In a weft detecting system for a narrow ware loom having a shuttle moving to a shuttle block during loom operation, a quill rotatable on the shuttle and provided with weft having an outer part thereof wound on the quill in one direction

and having another inner part thereof wound on the quill in the reverse direction, a detector on the shuttle normally supported in non-stopping position when the weft is taut but moving to stopping position when the weft is slack, the weft when being unwound from said outer part thereof being normally taut to support the detector in non-stopping position, the weft when starting to unwind from said inner part thereof becoming slack and incapable of supporting the detector, whereupon the detector moves to stopping position, and means dependent upon the detector being in stopping position to effect loom stoppage.

10. In a weft detecting system to detect a predetermined degree of exhaustion of weft on a quill rotatably mounted in a shuttle movable along the lay of a narrow ware loom, said quill having an outer winding of weft of one hand and an inner winding of the opposite hand under the outer winding, a weft detector in the shuttle held in non-indicating position so long as weft is taut and is being unwound from said outer winding but moving to indicating position due to slackness of the weft when the latter during the unwinding thereof reaches said winding of opposite hand, and means effecting loom stoppage incident to movement of the detector to indicating position.

11. In a weft detecting system for a narrow ware loom operating with a shuttle, a weft quill rotatable on the shuttle having an outer layer of weft wound on the quill in one direction covering an inner layer of weft wound on the quill in the opposite direction, a weft detector normally held in non-stopping position by weft which is normally taut when unwinding from said outer layer, the weft when unwinding from said inner layer becoming slack, whereupon the detector moves to stopping position, and means effecting loom stoppage when the detector is in stopping position.

12. In a weft detecting system for a narrow ware loom operating with a shuttle moving along a lay, a weft quill rotatable on the shuttle having an outer layer of weft wound on the quill in one direction covering an inner layer of weft wound on the quill in the opposite direction, a weft detector in non-stopping position when the weft is taut and moving to stopping position when the weft is slack, the weft when unwinding from said outer layer being normally taut and when unwinding from said inner layer being slack, and means dependent upon the detector being in stopping position and movement of the shuttle along the lay to effect loom stoppage.
